CLAIM

The ornamental design for a money holder, as shown and described.

DESCRIPTION

FIG. 1 is a top perspective view of a first embodiment of the design;

FIG. 2 is a bottom perspective view of the first embodiment of the design;

FIG. 3 is a bottom plan view of the first embodiment of the design;

FIG. 4 is a side elevational view of the first embodiment of the design; and,

FIG. 5 is a top plan view of a money holder showing a second embodiment of my new design which is the same in appearance as that of FIGS. 2 through 4 except for the top surface.
